APPARATUS FOR MAKING CARTRIDGE
CASING BLANKS OR THE LIKE

George Albert Lyon, Allenhurst, N. J.

Original application January 12, 1942, Serial No. 426,453, now Patent No. 2,360,354, dated October 17, 1944. Divided and this application March 18, 1946, Serial No. 655,119

4 Claims. (Cl. 78—60)

1

This invention relates to a metal coining apparatus and more particularly to a coining die for use in the manufacture of cartridge casings, such as those used in the shells for the 40 mm. Bofors anti-aircraft gun.

An object of this invention is to provide an improved coining apparatus which could be used in the economical manufacture of a circular or cylindrical metal object from a square blank or slab.

Another object of this invention is to provide an improved coining die for shaping from a predetermined blank a coined circular article of predetermined depth and in which the metal is caused to flow during the coining operation in such a direction as not to affect detrimentally the get-up of the article preferably made from the coined blank.

The subject-matter of this invention has been divided from my Patent No. 2,360,354 issued October 17, 1944, and is a continuation of my co-pending patent application, Serial No. 471,665, filed January 8, 1943, now abandoned.

Heretofore, in the manufacture of 40 mm. Bofors cartridge casings and the like, it has been the practice to punch out circular flat blanks from slab or sheet material, each blank having a predetermined weight and metal content commensurate with the size of the casing to be made therefrom by subsequent cupping of the blanks and drawing of the resultant cups. Such round blanks can obviously not be punched out contiguously. A network of slab material is left between the punched-out perforations. In particular, when heavy sheet or slab material is used, it is necessary to space each round blank a considerable distance from the adjoining blanks in order to have sufficient remaining material for a hold-down during the cutting through of the thick stock. Thus from a brass slab 91/4 inches long, 12 $\frac{1}{8}$ inches wide, and 0.687 inch thick, weighing 259.46 pounds, 62 round blanks each weighing 2.215 pounds may be punched. These 62 blanks will weigh 137.33 pounds. The part of the slab left as scrap after the punching operation will weigh 122.13 pounds. In other words, the punched-out round blanks amount to only 53 percent of the original slab material and 47 percent of the slab material is wasted as scrap.

Actually, it has been the practice for the brass foundries to roll brass into slab form, anneal the rolled slabs thoroughly, then punch out the round blanks and anneal the blanks for three hours. Such prolonged annealing is made necessary by the severe working of the marginal blank portions

2

in the punching operation and leaves the blanks with a coarse crystalline structure. The annealed blanks are shipped to the casing manufacturer for further working.

In the previous practice of fabricating cartridge cases, the round blanks have been cut from heavy slab material having a thickness equal to the required bottom thickness of the finished casings. Cartridges for present day anti-aircraft guns are provided with head or closed ends much thicker than the side walls, which are made as thin as possible in order to keep down the weight of the cartridges, for enormous gas pressures are generated within the cartridge cases on firing. The tapered form of the cartridge cases tends to direct the gas pressure against the bottom and base of the casing. Further, the base of the cartridge cases is not supported laterally by the gun bore, which is countersunk to render the cartridge base accessible to ejector fingers. As a consequence, the bottom and base of the cartridge cases must be made thick enough to prevent rupture on firing. When, according to the standard prior art method, round blanks are punched from thick metal slabs, the cutting or punching of the thick slab results in a so-called "drag" on the slab material at the edge being cut, which is made evident by roughness and the presence of slivers of free metal and burrs at the cut edge. The internal structure of the marginal blank portions is also made irregular for some distance inward. These irregularities remain in the margin of the punched-out part through all the subsequent cupping and drawing operations. As a consequence, it has heretofore been found necessary to draw out the casing to a length much greater than that desired in the final cartridge and then to cut off between four and five inches of the open end so as to remove from the casing material characterized by a roughened surface, overlapping seams, and more or less free slivers or burrs of metal. Further, portions of this irregular or rough part of the blank are likely to break off in one of the drawing dies and may then so damage the casing as to necessitate its rejection. Due to the rapidity with which these casings are drawn on a large production basis, such a broken-off piece of metal in the die, if not observed, might easily damage many casings before its presence is detected.

The present invention aims to provide a die apparatus for use in the fabrication of metallic casings which is of such construction and arrangement that a square blank can be initially used instead of a round blank, and whereby some

of the disadvantages and difficulties noted above can be obviated.

In accordance with the general features of this invention, there is provided a die construction of a configuration to receive a sheared square blank cut from a metal slab thinner than the required bottom thickness of the ultimate article, and by which coining apparatus the metal of the square blank is caused to flow in such radial direction as to form a raised edge and to flow other metal inwardly to form a centrally bulging button having margins tapering to the raised edge; the raised edge being so formed that it may be conveniently trimmed thereafter from the coined blank leaving a circular coined blank which may be thereafter cut and drawn into the desired cartridge case shape.

In accordance with other features of the invention, there is provided, in a coining apparatus of the aforementioned character, cooperable die members so constructed and interrelated as to act on the blank in such a way that the material thereof is distributed and so work-hardened with the central portion of the blank as to provide for the enormously concentrated strains to which the base and bottom of a cartridge made from the coined blank will be subjected on the firing of shells made using such cartridge casings.

Other objects and features of this invention will more fully appear from the following detailed description taken in connection with the accompanying drawings, which illustrate a single embodiment thereof, and in which,

Figure 1 is a vertical cross-sectional view through a coining apparatus embodying the features of this invention and taken on substantially the line I—I of Figure 2, this figure also showing the coined blank in position between the coining dies;

Figure 2 is a plan view of the structure shown in Figure 1, as seen after the removal of the upper or male coining die member, and showing in plan the configuration of a blank coin from a square piece of metal;

Figure 3 is a cross-sectional view through a blank coined by the dies of my invention after the marginal edge has been trimmed therefrom; and

Figure 4 is a vertical cross-sectional view through a cup formed by a suitable cupping operation from the coined blank shown in Figure 3, and which cupping operation constitutes the initial upsetting operation in the series of operations employed to draw a cartridge casing therefrom.

As shown on the drawings:

As noted before, it is the aim of this invention to use a square blank sheared from a slab of metallic stock, such as brass or steel, instead of a circularly cut blank in the forming of drawn articles, such as cartridge casings.

I have found that the use of such a blank enables certain metallurgical advantages in the distribution of the strains and crystalline make-up of the article and, moreover, enables a saving in as much as fifty percent of the heretofore waste material.

After a blank of the desired size and thickness has been cut from a slab, it is placed in my novel coining apparatus, shown in Figures 1 and 2, with its corners fitting in the square corners of the lower die member shown in Figure 2. I shall now proceed to describe the coining dies.

The coining assembly includes an upper male die member 20, a lower die member 21, an indexing ring 22 cooperating with the lower die member 21 to form a female die member, and an indexing plate 23 from which the indexing ring is suspended. The male die 20 is generally cylindrical, terminating in a constricted end portion having a round end face including an outer annular flat surface 24 surrounding a frusto-conical annular surface 25 within which an annular surface 26 slopes toward a shallow central recess 27. The lower die member 21 is also generally cylindrical, terminating in a constricted end portion having a round end face equal in size and aligned with the end face of the male die member 20 and formed with an outer annular flat surface 28 coextensive with the surfaces 24 and 25 and a shallow central recess having walls 29 sloping very gently toward a flat bottom 30. The indexing ring 22 is countersunk on both sides of the constricted end portions of the die members 20 and 21. The indexing ring is flanged for suspension in an aperture 32 in the indexing plate 23. Registering bores 33 and 34 provided, respectively, in the indexing ring flange and in the indexing plate accommodate coil springs 35 tending to lift the indexing ring away from the indexing plate. Such lifting movement is guided by headed pins 36 screwed into the indexing plate margin around the aperture 32 and extending through close fitting bores 37 in the indexing ring flange, the pin heads limiting upward movement of the indexing ring.

For cooperation with the die members 20 and 21, the indexing ring extends between the surface 28 in the lower die member 21 and the surfaces 24 and 25 on the upper male die member, having its upper inner edge bevelled for avoiding impact thereagainst of the male die member surface 25. At 90° intervals the inner surface of the indexing ring is recessed, as indicated by the reference numeral 38, to receive the corners of a square blank. The indexing ring and its recesses are so proportioned that the square blank is wedged fast therein. When the male die member 20 is approximated to the die member 21 and the indexing ring, a square blank being wedged fast in the latter, then the sloping surfaces 26 and 29 bring about an inward radial flow of blank metal filling the recesses in the faces of the die members 20 and 21. At the same time, the marginal blank material between the blank corners is forced radially outward; the resulting metal article being designated by the reference numeral 40 and comprising a marginal "flash" portion derived from marginal blank material (including the blank corners). This "flash" portion extends inwardly to a line 41 generated by the edge forming the transition from the frusto-conical surface 25 in the male die member to the sloping surface 26. The article 40, when trimmed along the line 41, forms the button 45 of Figure 3 having tapering margins 46 and a central bulge 47 on one broad face. This button does not contain any marginal blank material whose internal structure has been affected by the original slab shearing, blank forming operation, for all such material has been forced outside the line 41 in the coining operation.

The function of the index plate in the above described coining and trimming operations is to carry the index ring with the blank wedged fast therein from the various operating stations at which, respectively, placing of a blank in the ring,

coining, and trimming are effected. It should be noted that the index plate carries the index ring and the blank wedge therein as a unit from one station to another. The springs 35 lift the index ring off the die member 21 after the coining operation, when the male die member 20 recedes from the die member 21, the heads of the pins 36 limiting this upward movement of the index ring at a point where the index ring still remains centered in the index plate aperture 32.

Before the button 45 is subjected to a further working, it is annealed so as to compensate for the hardness resulting from the cold working. After the button 45 has been annealed, it is placed in suitable press equipment, central bulge downward, and is drawn into the shape of the cup designated generally by the reference numeral 50 in Figure 4. In this cup, the tapering margins 46 of the button 45 have been drawn into the wall 51 of the cup and the central button portion including the bulge 47 have been formed into the bottom 52 of the cup. The squeezing or coining operation having established in the coined blank a grain or crystal structure patterned after the spokes of a wheel in that the lines of flow of the crystals extend to and converge at the center of the blank, this same grain structure is carried over into the cup 50, the lines of the grain structure extending from the center of the bottom 52 around and up vertically through the side wall 51 so that the lines of the crystals all extend in substantially the same direction. This eliminates a potential point of weakness at the junction of the side wall 51 with the bottom 52 present in conventionally manufactured cartridge cases.

It should be noted that the inside side wall surface extends straight and with but little divergence from the vertical down to the line 53 in the base region and thereafter extends, still straight, but with slightly less steepness, to the bottom of the cup. The side wall 51 below the line 53 is thus made somewhat thicker than the rest of the side wall for the purpose of increasing the strength of the cup base.

After the aforesaid cupping operation, the cupped article is thereafter subjected progressively to a series of drawing operations for the purpose of elongating the wall of the cup to the length desired in the ultimate cartridge casing. Since such drawing operations do not per se relate to the coining apparatus herein claimed, it is not believed necessary to describe such operations in detail, especially since they are described and claimed in the aforesaid Letters Patent and pending application.

The internal or metallurgical make-up of the article is determined by the coining operation and is preserved during the subsequent operations so that the fibrous metal structure extends radially from the center of the bottom of the article up through the side walls.

Actually, I find that cartridge cases made by the use of my coining apparatus after the final annealing and normalizing operations have a hardness in the head and base region ranging from 115 to 105 Rockwell "F" while the straight open end section has a hardness of from 95 to 87 Rockwell "F".

I find that by using my invention the marginal trim portion to be scrapped amounts to about seven percent of the total stock used and that this figure actually includes whatever material from the end of a slab that may have to be scrapped.

A slab 12 $\frac{1}{2}$ to 12 $\frac{3}{4}$ inches wide and from 7 to 10

feet long may suitably be used for cutting blanks 4 inches square and $\frac{1}{16}$ inches thick, a 93 percent yield of such blanks being obtained. Another 21 percent of the original slab material is trimmed off the blanks after the coining operation, so that the total amount of wasted slab material is 28 percent as against the nearly 50 percent waste of slab material inherent in the prior art method.

The comparative cost of making blanks according to the conventional method and according to the present invention can be computed as follows. 500,000 pounds of standard blanks can be fabricated from 1,000,000 pounds of slab metal, for 21 $\frac{1}{4}$ cents per pound, being worth \$106,250.00, and 500,000 pounds of scrap being obtained as a by-product. According to the present invention, 1,000,000 pounds of slab material yield 720,000 pounds of the novel blanks together with 280,000 pounds of scrap. To these 280,000 pounds of scrap another 220,000 pounds, worth \$21,175.00 at 9 $\frac{1}{2}$ cents per pound, must be added to have 500,000 pounds of scrap for a new batch. Adding this \$21,175.00 to the \$106,250.00 cost of the 500,000 pounds of standard blanks gives a cost figure of \$127,425.00 for the 720,000 pounds of novel blanks of the present invention, which consequently will cost 17.7 cents per pound. Thus, conventional blanks weighing 2.215 pounds each will cost 47.07 cents each, while the novel blanks each weighing 2.13 pounds will cost 37.70 cents apiece. The saving will be 9.37 cents per blank when operating according to the present invention. Further, since the use of my present invention increases the yield of blanks from any given amount of slab material by 44 percent, the number of slab cutting, blank forming operations is reduced considerably.

It should be understood that the foregoing embodiment of my invention merely serves to illustrate the application of the principles of this invention, which are not limited to the specific example described. Thus, pentagonal or other polygonal blanks can be cut contiguously from slab material and coined in dies having indexing rings with an appropriate number of recesses for receiving the corners of the straight-edged blanks which are then trimmed, cupped and drawn, upset, tapered, and flanged to form the desired cartridge case.

I claim as my invention:

1. In a die for forming a cartridge case blank from a straight edged flat metal slab, the combination of a male die member having a face centrally recessed and marginally tapered away from the rim of the recess, another die member having a face opposed to and coextensive with the male die member, and an annular die member having an inside recessed at circumferentially spaced areas to receive the corners of said slab in wedged-fast relationship, said annular die member being interposed between the margins of said male die member face and said other die member face, to form with the latter die member a female die member capable of directly cooperating with said male die member to coin and squeeze said metal slab into a button having a thickened center tapering radially and raised extreme margins containing all the edge material of the original slab.

2. In a die for forming a cartridge case blank from a straight edged flat metal slab, the combination of a male die member having a face centrally recessed and marginally tapered away from the rim of the recess, another die member having a face opposed to and coextensive with the male die member face, and an annular die

member having an inside recessed at circumferentially spaced areas to receive the corners of said slab in wedged-fast relationship, said annular die member being interposed between the margins of said male die member face and said other die member face, to form with the latter die member a female die member capable of directly cooperating with said male die member to coin and squeeze said metal slab into a button having a thickened center tapering radially and raised extreme margins containing all the edge material of the original slab, said die further including means for guidingly lifting said annular die member to a predetermined level above said other die member after each coining and squeezing operation.

3. In a die for forming a cartridge case blank having a thickened center tapering radially to a thickened edge from a flat straight edge metal slab and including a male die member having a terminal face with a central recess and margins tapering away from the rim of said recess, the improvement including a female die member aligned with said male die member for direct cooperation therewith and including a member having a marginally flat face opposed to and coextensive with said male die member as well as an annular member having an inside recessed at circumferentially spaced areas to receive the corners of said slab in wedged-fast relationship and seated on the flat margins of the first mentioned female die member face to limit lateral

flow of slab material when the male die member is approximated to said female die member.

4. In a die for forming a blank for a metallic article from a polygonal flat metallic blank, in combination, directly cooperable aligned die members having opposed faces, one of said faces being centrally recessed and the other face having a contour other than convex, and an outer ring interposed between the margins of said opposed die faces and internally recessed at circumferentially spaced points for receiving the corners of said blank whereby when said blank is formed in said die, the corners of said blank are squeezed and wedged in said ring recesses so that the blank in its entirety may be removed with said ring.
